UNITED STATES PATENT OFFICE.

JOHN BLISS, OF LONDON, ENGLAND, ASSIGNOR TO C. C. WAKEFIELD & COMPANY,
LIMITED, OF LONDON, ENGLAND.

CLOSURE DEVICE FOR CONTAINERS FOR LIQUIDS.

1,356,502.

Specification of Letters Patent. Patented Oct. 19, 1920.

Application filed January 2, 1920. Serial No. 349,121.

To all whom it may concern:

Be it known that I, JOHN BLISS, a subject of the King of England, residing in London, England, have invented certain new 5 and useful Improvements in Closure Devices for Containers for Liquids, of which the following is a specification.

This invention is for improvements in or relating to a closure-device for containers 10 for liquids such closure-device being of the type which comprises a stopper having a screw-threaded portion which portion is adapted to be screwed into and to close the mouth of the container. The invention 15 has for its object to provide for a screw-stopper closure-device, a cover for that part of the mouth of the container which surrounds the stopper and comes into contact with the liquid when the same is being 20 poured from or into the container. The invention is particularly applicable to oil- or petrol-containers which are provided with a pouring spout extending from the mouth wherein the screw-stopper fits. When these 25 containers are carried on a motor-car or are left standing, dust accumulates in the spout (or other cupped-portion) adjoining the mouth, and consequently this is liable to get into the lubricant or other contents when 30 the container is next used.

According to this invention, a closure-device of the type described for containers comprises a screw-stopper and a plate carried thereby which is so placed and dimensioned that when the stopper is screwed home it lies over the cupped portion adjoining the mouth of the container with which the liquid comes in contact when pouring from or filling the container.

40 Preferably the plate is so mounted on the stopper that it can swivel on the same.

The term "cupped-portion" wherever it occurs herein is used to denote any trough or well-like portion, with or without a spout 45 or lip, which is adjacent to the mouth of the container and either stands above or is recessed to a lower level than that of the mouth and with which the liquid is likely to come into contact either when pouring from 50 or filling the container.

In the accompanying drawings which illustrate one method of carrying out this invention:—

Figure 1 is a perspective view of the stop-

per with the plate attached, viewed from the 55 top, and

Fig. 2 is a perspective view of the same parts viewed from the under-side.

The stopper A may be of the usual form which is hollow and made from thin sheet 60 metal. Surrounding the stopper is a plate B which is shaped to cover the usual spout and that cupped portion adjacent to or surrounding the mouth of the container, which mouth is screw-threaded to receive the stop- 65 per. The plate B is free to swivel on the stopper but is prevented from being withdrawn from the outer end of the stopper by the usual milled bead A¹, whereby the stopper is gripped for turning it, and is pre- 70 vented from displacement from the inner end of the stopper by a rib A². These stoppers are usually made up in two parts, the main body being formed as a cup, the open 75 end of which constitutes the outer end of the stopper, and then the mouth of the cup is covered in by a disk which is spun or clamped over the said outer end. The plate B can thus be introduced into position be- 80 fore the closing-plate is fixed on the outer 85 end, and then the said closing-plate which provides the milled bead, will prevent its withdrawal.

The plate B has a flange B¹ at the edge which is directed toward the inner end of 85 the stopper and serves to register the plate with the spout of the container when the device is in use.

It will be seen that by this means the covering-plate for the container-mouth is 90 always retained on the stopper, and when screwing the stopper home all that the operator has to do is to bring the plate into register with the mouth and its spout to insure that the same shall be covered. The 95 flange B¹ is sufficiently deep so that when the stopper is secured home the plate B cannot be lifted from the spout and moved angularly in relation thereto as the milled bead A¹ then keeps the plate down.

100 It will be appreciated that the plate may be of various shapes according to the kind of mouth the container is provided with and various means may be used to keep it on the stopper provided such means permit it to swivel unless the mouth of the container is such that it can be covered by a circular plate, in which case the plate need not

swivel but can be a fixture on the stopper. To use a circular plate for a mouth having a spout would necessitate the employment of a large plate relatively to the size of the stopper, which would be liable to become damaged and prevent the stopper from being properly screwed home.

The flange on the plate in addition to effecting registration with the spout, also 10 serves to prevent the entrance of dust underneath the plate, but the flange could obviously be interrupted if desired, and might in some cases merely take the form of two 15 projections arranged to register with opposite sides of the spout.

What I claim as my invention and desire to secure by Letters Patent is:—

1. A closure device for liquid containers having a spout extending laterally from the 20 mouth, which closure device comprises a screw stopper carrying a plate that is situated at right angles to the longitudinal axis of the stopper, is secured against axial move-

ment relatively to the stopper but is rotatable thereon, is shaped to cover the said 25 spout, and is so positioned on the stopper that when the latter is screwed home and the plate is brought over the spout, it is held in place by the stopper, substantially as described.

2. A closure device for liquid containers having a spout extending laterally from the mouth, which closure device comprises a screw stopper carrying a plate that is situated at right angles to the longitudinal axis 35 of the stopper, is secured against axial movement relatively to the stopper but is rotatable thereon, has a lateral projecting lip shaped to register with the said spout, and has a dependent flange to inclose the 40 sides of the mouth of the container and the spout, substantially as described.

In testimony whereof I affix my signature.

JOHN BLISS.
